ADJUSTABLE CARRIAGE FOR SAW MILLS.

No. 358,899.

Patented Mar. 8, 1887.

UNITED STATES PATENT OFFICE.

GEORGE STRONG, OF SOUTH ROCKWOOD, MICHIGAN.

ADJUSTABLE CARRIAGE FOR SAW-MILLS.

SPECIFICATION forming part of Letters Patent No. 358,899, dated March 3, 1887.

Application filed August 3, 1886. Serial No. 209,922. (No model.)

To all whom it may concern:

Be it known that I, GEORGE STRONG, of the village of South Rockwood, in the county of Monroe and State of Michigan, have invented new and useful Improvements in Adjustable Carriages for Saw-Mills; and I declare the following to be a full, clear, and exact description of my present invention, and one that will enable others skilled in the art to which it appertains to make and use the same, reference being had to the accompanying drawings, which form a part of this specification.

My invention relates to carriages for saw-mills, and to those which are designed more especially for cutting stave-bolts.

The following is a description of my improvement, which will be fully understood, when taken in connection with the annexed drawings, in which—

Figure 1 is a perspective view of the machine, showing the carriage in position for making a perpendicular cut. Fig. 2 is a side elevation showing the carriage in position for cutting radially with respect to the center of the log or bolt. Fig. 3 is a cross-section of one of the arms C and its knee. Fig. 4 shows the end of a log or bolt having parallel cuts, and Fig. 5 is a similar view of a bolt as cut by my improvement.

Referring to the annexed drawings by letter, A designates the traveling platform, to which is attached an adjustable carriage.

B B designate the standards, which afford journal-bearings for a horizontal shaft, F, to which are secured the arms C C of a carriage, upon which arms are movable knees D. These knees are suitably guided on their arms, and to their bases are secured racks a, with the teeth of which engage spur-wheels H, that are keyed on a transverse shaft, E, the ends of which have their bearings in said arms C C.

At or near the middle of the length of the shaft E is keyed a spur-wheel, I, with which engages a pawl that is pivoted to a hand-lever, N, which is applied to vibrate on shaft E. When the said pawl is engaged with the wheel I and the lever N vibrates, the knees D will be moved forward and the stuff fed up to the saw f. Each knee D is provided with a dog, P, for properly holding the stuff upon the arms C C. The arms C C are rigidly connected together by transverse bars G G, to the

latter one of which is secured ears n, and to these ears a segmental rack, K, is pivoted, which is vertically movable in a guideway, z, in one of the beams of the platform A. The teeth of the rack K engage with a spur-wheel, J, which is keyed on a shaft, R, that is journaled in the cross-beams S S of the platform A, and on one end of the shaft R is secured a hand-lever, M, provided with a pawl which engages with notches d in a sector, L, which is secured to the platform A. By these means the arms C C can be adjusted and secured in different planes, as indicated by the aid of dotted line 1 1 on Fig. 2. The platform A is mounted on wheels e, which are guided by rails secured upon tracks T.

The machine above described is designed for cutting staves in such manner that there will be no staves known as "wash-board staves." In practice it is designed to cut the logs into lengths suitable for stave-lengths. These are put one at a time on the carriage when in the horizontal position shown in Fig. 1, in which position the perpendicular cut is made. After the log is thus cut one half is placed on the carriage with its smooth face down, as indicated in Fig. 2.

It will be observed that the bolts are not cut squarely through the log, as in Fig. 4, but on an angle, as shown in Figs. 2 and 5, the different angles being obtained by raising or lowering the back end of the carriage, as above described.

Having described my invention, I claim—

The combination, with the connected vibrating arms C, provided with knees adjustable, as described, of the traveling platform A, the segmental rack K, pivoted to the rear cross-bar of said arms and guided below, the spur-wheel J, engaging with said rack, the hand-lever on the shaft of said wheel provided with a pawl, and the notched sector L, with which the pawl engages, all substantially as and for the purposes described.

In testimony that I claim the above I have hereunto set my hand and affixed my signature, in presence of two witnesses, at Detroit, Michigan, this 30th day of July, A. D. 1886.

GEORGE STRONG.

In presence of—

G. W. HAYS,

ABRAM VAN VRANKEN.
